UNITED STATES PATENT OFFICE

2,106,640

SANDWICH WRAPPER

Anthony Kovalik, Pittsburgh, Pa.

Application February 4, 1937, Serial No. 124,116

4 Claims. (Cl. 229—87)

This invention relates to what is believed to be a new and novel sandwich or lunch wrapper, and the preferred embodiment of the invention pertains to that subdivision in this line of endeavor which has to do with a type of lunch packaging wrapper readily usable by the housewife and equally desirable for handling by a workman of the type ordinarily called upon to carry his lunch to the job.

10 Stated otherwise, the inventive conception has to do with a duplex wrapper and tie assembly which though usable in other lines of endeavor, for wrapping various types of articles, is most satisfactorily employed, to the mutual advantage 15 of all concerned, when used as a wrapping or packaging device for a sandwich and other articles constituting a so-called working man's lunch.

Indicated along structural lines, the specific embodiment of the invention is characterized by 20 main and supplementary wrappers, wherein the inner wrapper is in the nature of a sheet of wax coated paper, "Cellophane", or equivalent material, and the outer binding wrapper of a more durable, substantially weatherproof texture such 25 as heavy wrapping paper, there being a unique cord binding or tying means associated with these features.

A further feature of the invention has to do with the adoption and use of a tying cord which 30 may be used over and over and which is releasably associated with the outer wrapper and held conveniently in place by a tab-like loop.

Other features and advantages will become 35 more readily apparent from the following description and drawings.

In the accompanying drawings, wherein like numerals are employed to designate like parts throughout the views:

Figure 1 is a top plan view of a structural 40 assemblage perfected in accordance with the principles of my ideas showing the inner and outer wrappers laid flat in readiness for packaging the lunch.

Figure 2 is what may be called a bottom or 45 back plan view of the arrangement depicted in Figure 1, showing to advantage the retention loop for the tying cord.

Figure 3 is a central fragmentary sectional 50 view which may be said to be taken approximately on the plane of the line 3—3 of Figure 2.

Figure 4 is a perspective view showing the 55 assemblage with the inner wrapper embracing the sandwich or other articles.

Figure 5 is a view showing the completely tied package ready for carrying purposes.

Figure 6 is a view like Figure 5, but calculated to bring out to better advantage the method of tying.

Figure 7 is a perspective view of an assembly type showing the tensioning rubber strap or band forming a part of the double section tying cord.

In the drawings the outer heavy paper wrapper, which may be of appropriate texture and proportions, is denoted by the numeral 8. Glued 10 or otherwise fastened to this at its center, as indicated at 9 in Figure 3, is the inner companion or complementary wrapper 10. This is of an area slightly less than the outer wrapper and is preferably of "Cellophane", waxed paper, or some 15 equivalent, substantially moisture-proof sandwich wrapping paper. Incidentally, in Figure 1, I have diagrammatically illustrated how the sliced or parted sandwich is to be placed at the approximate center of the inner wrapper, after 20 which it is wrapped up around its marginal edges to assume the package arrangement depicted in Figure 4. Then the outer wrapper is brought up around the inner wrapper to form the complete package in a well known manner, as shown for 25 example in Figures 5 and 6. The main thing that we are concerned with here is the provision of inner and outer complementary wrappers of varying proportions and kinds of material.

The tying means for the now folded or wrapped 30 package is essentially composed of three main features. For example, as shown in Figure 7, we are here concerned with a rubber band of suitable length, as indicated at 11. This is preferably reinforced by protective metal clips 12 35 mounted on opposite apertured ends thereof. These reinforcing cleats serve to accommodate the knotted inner ends 13 of the two lengths of cord. The outer free ends are denoted, as a matter of convenience by the numerals 14. The 40 outer wrapper, as shown to advantage in Figures 2 and 6, is provided at its center with a retention loop 15 glued or otherwise secured in place, as indicated at 16. This is preferably a paper loop to render it inexpensive. In practice, therefore, 45 the rubber band is inserted through the loop so that it occupies the approximate position shown in Figure 3, wherein it is properly anchored or retained in position and is also properly located to keep the cords under resilient stress and strain 50 and to thereby maintain the package well tied. The customary method of tying shown collectively or progressively in Figures 5 and 6 is resorted to, whereupon the free ends of the cords are brought together and tied into a readily discon- 55

nectible bow knot. Of course, a tying cord of this type can be used over and over. Ordinarily, the package itself is of a disposable paper type, so it is obvious that the papers may be so manufactured as to permit the package to be used repeatedly when not unduly soiled.

The essence of the invention resides in the provision of the interconnected central rectangular sheets of paper forming the inner and outer 10 so-called wrappers, the outer one being durable and the inner one of a substantially weather-proof waxed variety. In conjunction with this is the double length tying cord characterized by the resilient rubber band which provides the desired tying action if and when tied as illustrated in Figures 5 and 6.

It is thought that the description taken in connection with the drawings will enable a clear understanding of the invention to be had. 20 Therefore, a more lengthy description is thought unnecessary.

While the preferred embodiment of the invention has been shown and described, it is to be understood that minor changes coming within 25 the field of invention claimed may be resorted to if desired.

I claim:

1. As a component part of a lunch packaging assembly of the class described, a tying device 30 comprising a length of rubber, reinforcing metal cleats attached to the opposite ends thereof, said cleats being apertured, and a pair of cords knotted at their inner ends and passing through the aper-

tured cleats, the free ends of the cords being adapted to be tied together in the manner and for the purposes described.

2. As a new article of manufacture and as a component part of a lunch packaging wrapper of 5 the class described, a tying unit comprising a length of rubber, reinforcing metal cleats attached to opposite ends thereof, and a pair of tying cords attached at their inner ends to said cleats, the free outer ends of said cords being 10 adapted to be tied together in the manner and for the purposes described.

3. As a new article of manufacture and as a component part of a tying device of the class described, a length of rubber, reinforcing metal 15 cleats attached to the opposite ends of said rubber, said cleats being apertured and adapted to accommodate knotted ends of associated tying cords.

4. Lunch packaging wrapper means of the class 20 described comprising a substantially rectangular sheet of wrapping paper, a tab having its opposite ends fastened to one side of said paper, said tabs defining a retention and guiding loop being located at the approximate central area of said sheet, a tying unit comprising a rubber band slidably and releasably engaged with the loop and coacting therewith in intersecting relationship, and tying cords attached at their inner ends to 25 opposite ends of said rubber band in the manner and for the purposes described.

ANTHONY KOVALEK.
